UNITED STATES PATENT OFFICE.

CHARLES E. GREEN AND JOHN H. BODWELL, OF NEWARK, NEW JERSEY.

IMPROVEMENT IN FERRULES.

Specification forming part of Letters Patent No. 142,461, dated September 2, 1873; application filed February 11, 1873.

To all whom it may concern:

Be it known that we, CHARLES E. GREEN and JOHN H. BODWELL, both of the city of Newark, county of Essex and State of New Jersey, have invented certain new and useful Improvements in Ferrules; and we do declare the following to be a full, clear, and exact description of the same, reference being had to the accompanying drawings and to the letters of reference marked thereon and forming part of this specification, in which—

Figure 1 is a side view of a ferrule combining our improvements. Fig. 2 is a vertical sectional view of the same.

This invention relates to that class of ferrules used upon paint and varnish brushes to bind and secure the bristles; and consists in making the ferrules of corrugated sheet metal, such as brass, tin, or other light metal, in one or more thicknesses, and soldered together,

which may be done by immersing them in the solder.

The ferrule, being corrugated, imitates the twine or wire, and holds the bristles just as securely, and is much more durable, not so liable to give way, and can be manufactured at about one-half the cost of the ordinary wire-ferrule.

What we claim as new, and desire to secure by Letters Patent, is—

As a new article of manufacture, a corrugated sheet-metal ferrule for paint or varnish brushes, constructed as herein shown and described.

CHARLES E. GREEN.
JOHN H. BODWELL.
